UNITED STATES PATENT OFFICE.

RUSSELL H. BOWEN, OF PHILADELPHIA, PENNSYLVANIA, ASSIGNOR TO THE AMERICAN PULLEY COMPANY, OF PHILADELPHIA, PENNSYLVANIA, A CORPORATION OF PENNSYLVANIA.

METHOD OF SECURING TOGETHER THE COMPONENT PARTS OF METALLIC SPOOLS OR REELS AND APPARATUS USEFUL TO THIS END.

Application filed January 4, 1924, Serial No. 684,364. Renewed September 11, 1925.

To all whom it may concern:

Be it known that I, RUSSELL H. BOWEN, a citizen of the United States, residing at Philadelphia, in the county of Philadelphia and State of Pennsylvania, have invented certain new and useful Improvements in Methods of Securing Together the Component Parts of Metallic Spools or Reels and Apparatus Useful to This End, wherefore the following is a specification, reference being had to the accompanying drawings.

This invention is concerned with securing together the component parts of metallic spools or reels of the type wherein the barrel member is provided with projections or tabs engaging in apertures of the opposite end flange heads. In accordance with the usual method employed heretofore in accomplishing this purpose, the portions of the tab ends projecting through the flange heads were upset or riveted by manual hammering, or by use of a power press to the same end. This procedure was often attended by distortion of the spool barrel especially in the case of spools or reels constructed from comparatively thin sheet metal.

The purpose of my invention is to overcome the objection above pointed out, and this desideratum I secure by heating the projections or tabs sufficiently to permit of their being subsequently upset or spread by application of light pressure.

In the drawings, Fig. I is a perspective view of the type of spool or reel to the assembling of which my invention is directed, one of the end flange heads being shown separated from the associated parts so as to avoid concealment of the characteristic details of the structure.

Fig. II is an illustration in vertical section showing more or less diagrammatically, a typical embodiment of the apparatus of my invention with the spool or reel assemblage in place in readiness to be operated upon.

Fig. III shows, in end elevation, the appearance of the spool or reel after its component parts have been permanently secured together in accordance with my invention; and

Fig. IV is a detail sectional view on an

enlarged scale taken as indicated by the arrows IV—IV in Fig. III.

The spool or reel shown in Fig. I of the drawings comprises a barrel member 1, and separate end members or heads 5, 5. The barrel member 1 is fabricated from a sheet metal blank having integral short prolongation tabs 2 at intervals along opposite side edges, said blank being bent to cylindrical configuration with its ends meeting along a line 3. The heads 5 are likewise struck from sheet metal, the edges of the circular blanks from which they are formed being rolled to provide peripheral stiffening beads 6. Each head 5 has a concentric series of apertures 7 designed to receive the tabs 2 of the barrel member 1, and also a circumferentially flanged central aperture 8 so as to be mountable for rotation upon an appropriate axis or spindle.

The apparatus by aid of which I secure together the component parts of a spool or reel such as described above includes, as illustrated in Fig. II of the drawings, a metallic plate 10 that serves to support the spool reel assemblage in vertical or end-on position with one of the heads 5 resting directly upon it. The upper face of the plate 10 is formed with concentric circular grooves 11, 12 which constitute clearances respectively for the bead 6 of the near head 5 and the projecting tab ends 2 of the barrel member 1. The plate 10 is in circuit with an electric generator conventionally indicated at 13 and functions as an electrode in which capacity it is opposed by one or more relatively movable electrodes such as shown at 14 in the illustration. The electrodes 14 are preferably made cylindrical with their ends tapered as shown for operation upon the tabs 2, and any suitable means may be provided for their guidance and actuation in the manner hereinafter noted. The electric circuit previously referred to has interposed in it an appropriate switch 15 for controlling the current to the electrodes 14.

The operation of the apparatus as illustrated in Fig. II is as follows:

Assuming the spool or reel assemblage placed as shown in Fig. II and an electrode 14 in contact with an exposed projecting tab

end 2, the switch 15 is closed. When the tab 2 has been heated to the extent of rendering the metal semi-molten, the switch 15 is opened to intercept further flow of current in the circuit, and sufficient pressure is thereupon applied to the electrode 14 to spread or upset the softened metal within and over the flared aperture 7 of the head 5, the result of this procedure being shown 10 in Figs. III and IV. The final step in the operation, it will be readily appreciated, requires application of but slight pressure as compared to the blow of a hammer or to the action of a power press, so that the 15 possibility of distorting the barrel is entirely obviated. The shutting off of the heating current before the upsetting pressure is applied not only avoids needless heating of the head 5 and consequent risk of 20 overheating and deformation, but also obviates risk of collapsing the spool end by excessive pressure of the electrode 14 combined with over-prolonged heating. When the tabs 2 at one end of the spool or reel 1 25 have been upset as just explained, the assemblage is inverted upon the plate electrode 10 and the operation repeated precisely as before.

Having thus described my invention, I 30 claim:

1. The herein described method of assembling an all metal spool or reel wherein the barrel portion is provided with tabs engaging through apertures of the end flange heads, which consists in electrically upsetting the protruding ends of the tabs by combined application of heat and pressure.

2. The herein described method of assembling an all metal spool or reel wherein the 40 barrel portion is provided with tabs engaging through apertures of the end flange heads, which consists in passing heating current from an electrode through the protruding end of a tab until the tab is softened, 45 and then shutting off the current and applying pressure to upset the softened tab.

3. In apparatus for securing together the component parts of a sheet metal spool or reel wherein the barrel member is provided 50 with spuds engaging through apertures in the flange head members, the combination of a plate electrode for supporting the spool or reel assemblage end-on, and an opposing electrode movable into contact with the tabs 55 projecting through the opposite end flange or head of said spool or reel.

4. In apparatus for securing together the component parts of a sheet metal spool or reel wherein the barrel portion is provided 60 with prolongation spuds engaging through flared apertures in the flange head members, the combination of a plate electrode for supporting the spool or reel assemblage end-on, said plate electrode being concentrically recessed to accommodate a peripheral bead of the near flange head and the aforesaid tabs projecting therethrough, and an opposing electrode movable into contact 65 with the tabs projecting through the opposite end flange head of the spool or reel.

In testimony whereof, I have hereunto signed my name at Philadelphia, Pennsylvania, this 27th day of December, 1923.

RUSSELL H. BOWEN.
